UNITED STATES PATENT OFFICE.

RICHARD P. ELLIOTT, OF BOSTON, MASSACHUSETTS.

CARBID-FEED ACETYLENE-GENERATOR.

1,167,986.

Specification of Letters Patent. Patented Jan. 11, 1916.

Application filed May 7, 1910. Serial No. 559,955.

To all whom it may concern:

Be it known that I, RICHARD P. ELLIOTT, a citizen of the United States, residing in Boston, county of Suffolk, commonwealth of Massachusetts, have invented certain new and useful Improvements in Carbid-Feed Acetylene-Generators, of which the following is a specification, reference being had to the drawings accompanying the same and forming a part thereof.

My invention relates to carbid-feed acetylene generators, and particularly to the feeding valve and devices for controlling the same.

The objects of my invention are to produce a pressure-controlled feeding mechanism suitable for large or stationary carbid-feed acetylene generators adapted to feed granulated carbid in quantities proportionate to the volume of gas drawn from the generator; to provide a flexible valve and a hard or metallic seat so that when closed they will make a gas-tight closure; to protect the feeding valve from the weight of carbid in the carbid-chamber when it is full; to provide means to prevent the carbid from flowing into the water in case of injury to the pressure-controlled mechanism; and for protecting the pressure-controlled diaphragm from contact with the carbid, together with other objects which will be pointed out in the specification.

In the drawings the figure represents a vertical section of the carbid-chamber, the feeding mechanism, and other mechanisms connected to the carbid-chamber.

In the drawings accompanying this specification, 1 represents the vertical wall of the carbid-chamber; 2 is a casting secured to the upper ends of the wall 1; 3 is the inclined bottom of the carbid-chamber; 4 is a vertical portion secured to the outside of the wall 3 at its upper end, its lower end being secured to a casting 5. The casting 5 is provided with the threaded portion 6 and a groove 7 in which may be secured a ring of suitable packing for making a gas-tight closure and adapted to be secured to a suitable water tank.

The casting 2 of the carbid-chamber is provided with a recess 20 to receive a cap 21, the cap 21 being secured to the portion 22 of the casting 2 by screws 23, 23, etc. The cap 21 has a screw threaded hole 24 in its center adapted to receive the threaded feeding screw 25, the upper end of the feed-

ing-screw being provided with a crank-handle 26.

The valve mechanism consists of the portion 27 which is of a diameter to fill the valve-seat 28. The valve-seat 28 is flared, being slightly larger in diameter at the bottom. The portion 27 is provided at its lower end with the portion 29 which has a downwardly projecting rib 30 which sinks into the flexible valve 31 and serves to hold the valve in position against displacement. The portion 29 is provided with a shouldered portion 32 and a threaded portion 33 which is adapted to have screwed upon it the clamping portion 34. This clamping portion 34 is provided with the raised ring 35 adapted to sink into the flexible valve 31 and assist in securing it in position. The valve 31 has a round hole in its center in which is inserted a metal sleeve 36 so that the upper end of the sleeve will contact with the portion 29, and the lower end with the portion 34. This is in order that the portion 34 may be screwed firmly upon the portion 29 and held tightly by engaging the sleeve 36 between them. The portion 34 has a small hole 37 threaded to receive the threaded portion on the lower end of the valve-stem 38. The valve-stem 38 extends upwardly through a flexible disk 39 made of leather or other suitable material, the hole in the disk 39 being small enough to tightly fit upon the valve-stem 38 and form a flexible dust-proof closure. The outer edges of the disk 39 are clamped between the end of the tube 40 and the periphery of a cup-shaped disk 41; the cup-shaped disk being of the same diameter as the outside of the tube 40. The disk 41 and the flexible washer 39 being held firmly in place by the cap 42, the inside diameter of which is such as to fit tightly upon the outside of the tube 40.

The valve rod 38 is threaded at its upper end and firmly screwed into the plug 43 which in turn is secured in the spring-case 44. The upper end of the spring-case has secured to it a flange 45 which is threaded upon its upper end and has screwed thereon the ring 46. There is a metal washer 47 under the ring 46 between which and the flange 45 is clamped a flexible diaphragm 48. The outer edge of the diaphragm 48 is clamped firmly between the portion 22 of the casting 2 and the periphery 49 of the cap 21. The diaphragm 48 is made of a flexible stretchable material, such as rubber,

and the edges and the center of the dia-phragm are secured to the respective parts hereinbefore enumerated in such manner as to make a gas-tight closure. The cap 21 is provided with air holes 50, 50, so that there will not be a vacuum created in the space between the diaphragm and the top of the cap. The casting 2 has a downwardly projecting cone-shaped portion 51, which, with the portion 21, forms a chamber in which the diaphragm 48 is secured, which arrangement prevents carbid in the carbid-chamber 52 from coming in contact with the dia-phragm. In order that the gas pressure may reach to the under side of the diaphragm, I provide a pipe 53 which is secured in the wall 3 at its lower end, and in the wall 51 at its upper end in manner to make a gas-tight closure. By this arrangement, dust from carbid in the carbid-chamber, or the carbid, cannot come in contact with the dia-phragm, yet gas as generated by dropping carbid into the water-tank 8 through the feeding-valve can rise and flow through the pipe 53 to the diaphragm communicating the pressure to the under side of the dia-phragm, and when a predetermined pressure has been reached the valve will be pulled upwardly by means of the diaphragm 48, the spring-case 44, valve-stem 38, and the flexible valve 31 attached to the valve-stem pulled upwardly until its periphery closes the space in the valve-seat 28. Should any thing happen to the diaphragm so that the gas would pass through it, and the pressure not be exerted upon it to pull the valve upwardly, the feeding spring 54 would push the valve-stem downwardly until the portion 27 of the valve would close the valve-seat 28 and shut off the flow of carbid.

To protect the valve 31 and portion 27 from the accumulated weight of carbid in the carbid chamber when full, I provide a flaring shelf 55 which is secured to the tube 40 and flares outwardly, leaving an annular space 56 between its edge and the bottom 3 of the carbid-chamber. The tube 40 is secured firmly in the hub 57 which is formed upon the downwardly flaring partition 51.

As the gas is generated, it passes up through a tube 58 secured in the wall 3 of the carbid-chamber, its upper end projecting upwardly into a threaded hole 59 in the casting 2, the hole being larger in diameter than the outside of the tube 58, to provide a gas passage from the top of the tube 58 into the carbid-chamber 52. The threaded hole 59 is closed by the plug 60. The gas passes from the tube 58 into the carbid-chamber and down through the carbid, if the chamber is full, to the lower end of the tube 61 and up through a filtering material 62 composed of fibers or felt, or preferably of sheep's wool, thence out through the valve 63 to the supply pipe attached to the valve 63.

The operation of my device is as follows:— The water-tank is first filled with clean wa-
ter, and the carbid-chamber filled with car-
bid. But before the operation of filling the
carbid-chamber with carbid is commenced, 70
the feeding-screw 25 should be screwed up-
wardly to its uppermost position, thereby
drawing the flexible portion of the valve
31 into the seat 28, when the chamber may
be filled with carbid. 75

To start the generation of gas, the feed-
ing-screw 25 is screwed downwardly, com-
pressing the spring 54, and through it push-
ing the spring-case 44, the valve-rod 38, and
the valve 31 downwardly, as shown in Fig. 80
1, so that the carbid can flow outwardly into
the water-tank. When the carbid reaches
the water-tank and the generation of gas
commences, the gas flows through the pipe
53 to the under side of the diaphragm, and
if the pressure reaches a point to overcome
the tension of the spring 54 the diaphragm
pulls the valve 31 upwardly into its seat 28
and shuts off the flow of carbid. The feed-
ing operation is repeated each time the gas 85
is drawn off, and the pressure of gas in the
generator falls below the tension of the
spring 54. 90

I do not limit myself to the exact form,
location or arrangement of the parts as 95
shown in the drawings, as various changes
may be made in these respects without de-
parting from the spirit of my invention.

What I claim is—

1. In an acetylene generator, a carbid-
feed mechanism comprising a carbid cham-
ber and a downward tapering opening in the
bottom of the carbid-chamber to form a
valve seat; an inclosed chamber formed at
the top of the carbid-chamber having a flexi-
ble diaphragm located in the middle thereof,
the edges of the diaphragm being secured 100
in said inclosed chamber to form a gas-
tight closure; a tube extending downwardly
from the inclosed chamber and secured
therin with a gas and dust-tight closure; 105
an outwardly and downwardly flaring metal
support secured to the lower part of said
tube; a cup-shaped guiding washer secured
on the lower end of said tubing; a flexible 110
washer secured to the lower end of said tube
having a hole therethrough to receive a
valve rod; said valve rod; a spring-casing
secured to the upper end of said valve rod,
the upper end of said spring-casing being 115
secured in the center of the diaphragm with
a gas-tight closure; a valve mounted upon
the lower end of said valve rod having se-
cured therein a flexible ring formed to seat
in the valve seat with a carbid and water-
tight closure; a metal flange formed on the
top of said valve of a diameter approxi-
mately the same as the diameter of the valve
seat and adapted to close it to prevent carbid
falling through the valve seat when it is 120
125
130

- 5 moved downwardly into said valve seat; a compressible spring mounted in the spring-casing; a screw threaded into the top of the carbid-chamber and arranged to press against the top of the compressible spring; means for turning the screw downwardly against the end of the spring to compress it so as to move the valve downward away from the valve seat; and a passage from the 10 space below the bottom of the carbid-chamber to the inclosed chamber in which the diaphragm is located so that gas pressure in the generator can be communicated therethrough to the under side of the diaphragm.
- 15 2. In an acetylene generator, a water-tank and a carbid-chamber; a cylindrical opening in the bottom of the carbid-chamber through which the carbid is fed to the water; a flexible valve for closing said opening; a fixed 20 flaring shelf in said carbid-chamber for partially supporting the weight of the carbid, located just above the valve seat in the bot-
- tom of the carbid-chamber; a compressible spring for opening the valve; a pressure-controlled diaphragm for closing the valve; 25 a diaphragm chamber in which said diaphragm is mounted having a dust and gas-tight wall between it and the carbid chamber; a passage communicating with the gas space in the generator and the underside of 30 the diaphragm; a tube through which the gas can flow from the water-tank to the top of the carbid-chamber; and an outlet from the carbid-chamber having a fibrous filtering material located therein. 35

In testimony whereof, I have hereunto set my hand, in the presence of two subscribing witnesses, this the 5th day of May, A. D. 1910.

RICHARD P. ELLIOTT.
